UNITED STATES PATENT OFFICE.

HARRISON HUSTON AND ELWIN J. MARTIN, OF IDAHO SPRINGS, COLORADO.

MACHINE FOR OPERATING ROCK-DRILLS.

SPECIFICATION forming part of Letters Patent No. 396,745, dated January 29, 1889.

Application filed June 9, 1888. Serial No. 276,634. (No model.)

To all whom it may concern:

Be it known that we, HARRISON HUSTON and ELWIN J. MARTIN, citizens of the United States of America, residing at Idaho Springs, 5 in the county of Clear Creek and State of Colorado, have invented certain new and useful Improvements in Mechanism for Operating Rock-Drills, of which the following is a specification, reference being had therein to the accompanying drawings.

Our invention relates to a new and improved construction of mechanism for operating rotary drills, and its object is to furnish a mechanism for rotating such drills and for 15 feeding them forward in the material being acted on during rotation, which shall be simple and economical in construction, reliable and comparatively speedy in operation, with a high degree of efficiency for the amount of 20 power applied thereto, easily managed and operated, and durable in use; to which ends it consists in the features more particularly hereinafter described and claimed.

In the drawings is illustrated a drill-operating mechanism embodying our invention, in which—

Figure 1 is a top or plan view thereof; Fig. 2, a section on line *x x*, Fig. 1; Fig. 3, a side view; Fig. 4, a top view of the turn-table; Fig. 30 5, a section of the base and the turn-table on line *y y*, Fig. 1; Fig. 6, a section of a detail of construction.

In the figures, the reference-numeral 1 indicates what may be termed the "fixed base of 35 the operative mechanism," in that, while capable of rotation and adjustment to vary the angle at which the drill may be worked, it is fixed or stationary relatively to the devices for rotating and feeding the drill, as herein- 40 after described. This base 1 rests upon what may be termed the "turn-table" 4, pivoting thereon, so as to be capable of rotation by a pivot-pin, 2. From the under side of the base 1 lugs or bolts 3 depend, taking in and passing 45 through slots 5 in the turn-table 4, and having clamping-nuts 26 upon their outer end, so that the base 1 and turn-table 4 may be secured or clamped together at any desired relative position permitted by the length of 50 the slots 5. Upon the under side of the turn-

table 4 is a clamp, 6, of the usual construction, by which the turn-table may be secured rigidly to an ordinary extension-post or any other suitable base to support the drill and drill mechanism in the proper position.

55

Upon the base 1 are formed suitable guides or ways for the rotating and feeding mechanism to move or reciprocate in, such ways being here shown as the grooved guideways 7.

8 8 are the longitudinal bed-pieces supporting the drill mechanism proper, and formed to engage with, move upon, and be guided by the grooved guideways 7. To them are secured the cross-braces or bed-pieces 9 9 9,

forming with 8 8 a rigid firm bed or frame for the operative parts and affording suitable bearings therefor. The bed or frame may be further secured and braced by longitudinal pieces 10 10. The exact construction of such bed, however, is not a material part of the invention, so long as its construction be such

that it may be readily reciprocated and guided upon the base 1 and afford the suitable bearings or locations for suitable bearings for the parts to be placed thereupon.

75

Suitably journaled in bearings in or upon the frame or bed is the main shaft 11, to which is attached the main gear-wheel 12, furnished with a crank-handle, 13, for manual operation.

The gear 12 meshes with a gear, 14, on 80 the drill-spindle 15, suitably journaled in or on the movable bed or frame near its forward end, or at more than one point, if desired.

At its rear end, however, this drill-spindle 15, which is hollow, should be journaled either 85 within or upon the exterior of a hollow or tubular fixed bearing, 16, which is supported by a bracket, 17.

As here shown, the rear end of drill-spindle 15 is journaled within the fixed tubular bearing 16, and the latter should be so fashioned that a tube or hose from any convenient water tank or supply may be attached thereto, in order that water may pass into and through the hollow drill-spindle to aid in the 90 cutting and to wash the débris from the hole.

The gears 12 and 14 should be calculated 95 relatively to each other to give a high rate of speed to the drill, to which end they may connect directly, one being of several, even many 100

times the teeth of the other, or they may connect through intermediate gearing.

- Provision now being made for the rotation of the drill, there must also be means provided for feeding it forward, which means are arranged as follows: Upon the main shaft is second and smaller gear, 18, meshing with a gear, 19, on a feed-shaft, 20, suitably journaled in bearings in or upon the bed or frame.
- 10 Upon or near the outer or front end of this shaft 20 is secured a worm-gear, 21, which meshes with a rack, 22, on the fixed base 1. Then as power is applied to the main shaft 11 and gear 12 to rotate the drill motion is 15 also communicated through gears 18 and 19 to the worm 21, which, taking in the rack 22, causes the drill mechanism and its frame or bed to advance or move upon the fixed base 1. To enable a retrograde movement to be 20 given quickly, more expeditiously than possible with a reverse movement of the drilling mechanism, the rack 22 is not rigidly secured to the base 1, but pivotally, as at 27, a stop, 24, being arranged upon the base 1 to hold 25 the otherwise free end of the rack from movement in one direction, while a pivoted button or catch, 23, holds it securely when in locking position, as in full lines in Fig. 1, from movement in the other direction. The button and 30 the rack being turned, as in dotted lines in Fig. 1, the worm and the rack are disengaged and the sliding bed-pieces 8 8 and parts secured thereupon may be rapidly slid back in the grooved ways 7 7.
- 35 With fixed gears 18 19 and fixed worm 21 and rack 22 the rate of feed or forward movement of the drill would be fixed and constant relatively to its speed of rotation. As, however, the rate of cutting by the drill depends 40 upon the hardness and refractoriness of the material operated on, a constant speed being maintained, the feeding devices should be capable of variation, so as to feed more rapidly in soft rock, &c., and more slowly in the harder.
- 45 The rate of feed could be varied by changing the gears 18 19 so as to give more or less revolutions of the worm 21 to a given number of revolutions of the drill-spindle. We prefer, however, to use fixed gears 18 19 and vary the 50 rate of feed by changing the worm and its co-acting rack. For this purpose several worm-gears may be provided varying in pitch, they being constructed so as to be removably secured upon or to shaft 20. Such removable 55 attachment may be accomplished by having the worms made upon the exterior of cylinders which are internally screw-threaded, as shown at 28, such screw-thread taking in a corresponding thread on the end of shaft 20; or a worm may be rigidly secured to a part of the shaft 20, which in such case is divided, the two parts being united by a mortise and tenon, as shown at 25 in dotted lines, or by 60 the end of one part taking in a suitable socket 65 in the other part. In either of these ways

the worm may be readily and quickly changed to vary the feed to the quality of rock or material being operated on. At the same time the rack 22 may be changed, one being removed by simply unscrewing or unbolting at 70 the one point 27, and another corresponding to and adapted to mesh with the worm to be used being substituted and secured in position by one screw or bolt at the same point.

75 As illustrated, this drill mechanism is shown to be operated by hand-power applied to the crank. It, however, is equally applicable to a power-drill, for any suitable motor—steam, compressed air, electric, &c.—may be mounted 80 upon or secured to either the drill-spindle or the main spindle, or shaft 11, so as to communicate motion both to the drill and the feeding mechanism.

In practice the operation is as follows: The 85 turn-table 4, by means of the clamp 6, is secured at the proper angle or in suitable position upon an extension-post or other support, the fixed base 1 being turned thereon to the desired point and there clamped by means of 90 the nuts 26. The proper pitched worm and spaced rack for the rate of feed suitable for the rock to be operated on should be secured in their proper places. Power, either hand, by the crank 13, or by an engine located as 95 indicated, being now applied, the drill will be rotated and fed forward, so as to accomplish its work in a reliable manner and effectively.

Having thus described our invention, what 100 we claim is—

1. The combination of a fixed base provided with guideways, a bed or frame upon such base and moving in the guideways, a drill-spindle mounted in or on such bed or frame, 105 mechanism, as described, for rotating the drill-spindle, and a feed mechanism consisting of an interchangeable and removable worm-gear on the moving bed or frame, and a removable and interchangeable rack adapted 110 to mesh therewith and secured upon the fixed base, substantially as set forth.

2. The combination of a fixed base provided with guideways, a bed or frame adapted to move in such guideways, a drill-spindle 115 mounted in or on such frame or bed, mechanism, as described, for rotating the drill-spindle, and a feed mechanism consisting of a worm-gear on the moving bed or frame, and a pivoted rack on the fixed base, and stops 120 upon such base for holding the rack in operative position, substantially as set forth.

3. The combination of the base 1, having grooved guideways and the depending lugs or bolts 3, the bed or frame adapted to move 125 in such guideways, a drill-spindle mounted in or on such bed or frame, mechanism, as described, for rotating the drill-spindle, a feed mechanism consisting of a worm-gear on the moving bed or frame, a rack pivoted on the 130

base 1 and meshing with the worm-gear, and stops for holding the rack in operative position, the turn-table 4, having the curved slots 5, through which take the bolts or lugs 3, 5 having the nutted heads 26, and the pivotal connection 2 between the base 1 and turn-table 4, substantially as set forth.

In testimony whereof we affix our signatures in presence of two witnesses.

HARRISON HUSTON.
ELWIN J. MARTIN.
